UNITED STATES PATENT OFFICE.

WILLIAM L. McCRAY, OF BLUEFIELD, WEST VIRGINIA

LOCKING DEVICE FOR AUTOMOBILES.

1,131,720.

Specification of Letters Patent. Patented Mar. 16, 1915.

Application filed December 5, 1914. Serial No. 875,691.

To all whom it may concern:

Be it known that I, WILLIAM L. McCRAY, a citizen of the United States, residing at Bluefield, in the county of Mercer and State of West Virginia, have invented certain new and useful Improvements in Locking Devices for Automobiles, of which the following is a specification, reference being had therein to the accompanying drawing.

10 This invention relates particularly to devices for locking the swinging controller lever of automobiles, the general object being to provide a simple and effective device which can be readily attached, even by unskilled persons, to automobiles in use, and which cannot be removed or rendered ineffective by the hands or small appliances, or, in other words, without making it plain to any observer that wrong is being done.

20 Another object is to provide devices such that when not holding the controller lever they are practically out of the way, although still securely attached to the vehicle.

With these objects in view, a bar is pivotally attached to the fixed portion of the vehicle in such manner that while normally pendant it may swing into place alongside the lever and be locked thereto to prevent its movement in either direction.

30 In the accompanying drawings, Figure 1 shows the devices in side elevation and in operative position holding the controller lever against swinging. Fig. 2 is a plan view of the same devices. Fig. 3 is a perspective view showing a slide member seen also in Figs. 1 and 2. Figs. 4 and 5 show in elevation and plan, respectively, a modified bar and slide.

In Figs. 1, 2, and 3, A represents the controller lever of an automobile, B a portion of the seat or other fixed part, and C a forked bar pivoted near one end to the part B to swing in a plane substantially parallel to the plane of movement of the lever, so that the branches of the bar may be brought upon opposite sides of the latter. For pivotally supporting the bar, a plate D from which a long staple E projects perpendicularly, is fixed to the support B, preferably by screws or bolts which cannot be unscrewed from their inner ends. The outer portion of the staple passes through a hole in the bar, at some distance from its end, and forms the pivot on which the bar swings freely. On the intermediate portion of the staple slides a loose plate or guard F, and

the parts are so proportioned that when the bar is raised to horizontal position its end portion C' holds the loose plate in such proximity to the plate D that access to the screw or bolt heads is prevented, while if the bar be in vertical position and the plate F be moved outward, the fastenings are accessible.

Upon the forked portion of the bar is mounted a frictionally held slide G of general U-shape and preferably of steel. This slide is of such length that when it is moved outward until the web connecting its two branches meets the lever its free ends project beyond the lever far enough to permit the bail of a common lock G' to pass through suitable holes in both branches of both the slide and the forked bar. The slide is thus locked to the bar and the lever is securely held between the lock bail and the web at the inner end of the slide so that it can swing in either direction. Preferably the fork is made long and provided with bail-receiving apertures at short intervals, so that the device may be used, unchanged, upon different vehicles where the distance of the lever from a convenient point of support for the lever pivot varies greatly, the slide being moved along the bar until its apertures G² register with the proper apertures G³ in the fork.

When the lever is to be freed, the lock is removed and the forked bar drops to vertical position, as indicated in dotted lines in Fig. 1, where it offers little obstruction.

In some instances, the lock is connected to the end of one branch of the fork by a chain I, the chain and its fastening serving also to bar removal of the slide from the fork. In this case no portion of the device, unless it be the lock key, when a key lock is used instead of a combination lock, can be detached or lost.

The construction may be varied in different ways while preserving many advantages of the invention. For example, a simple bar C², Figs. 4, 5, may replace the forked bar, the slide G⁴, in such case having one branch replaced by a hook G⁵.

What I claim is:

1. In devices of the class described, the combination with a pivoted lever, of a bar pivoted to swing into position transverse to and alongside said lever and provided with devices to prevent its moving laterally from the lever and to prevent the lever from swinging in one direction, and a lock adapt-

ed to engage the bar and prevent the swinging of the lever in the opposite direction.

2. The combination with a pivoted lever, of a normally pendant bar pivoted to swing to a position transverse to and alongside the lever, a slide adjustable along the bar and adapted to embrace one side of the lever and obstruct its swinging except in one direction, and a lock for securing the slide to the bar and itself preventing the swinging of the lever in said one direction.

3. The combination with a pivoted lever, of a transversely perforated bar pivoted near one end to swing in the plane of the lever and having its end portion forked to embrace the latter, a transversely perforated U-shaped slide mounted upon the fork to prevent the swinging of the lever in one direction, and a lock adapted to secure the slide to the fork and bar the swinging of the lever in the opposite direction.

4. The combination with a pivoted lever, of a bar provided with a series of transverse perforations and pivoted to swing to a position transverse to and alongside the lever, a transversely perforated slide adjustable along the bar and adapted to embrace one side of the lever and prevent the lateral

separation of the two and the swinging of the lever in one direction, and a lock arranged to pass through the perforations in the slide and bar, obstructing the swinging of the lever in the opposite direction and locking the slide to the bar.

5. The combination with a pivoted forked lever, of a plate secured to a fixed support by suitable fastenings, a second movable plate adapted to cover and protect said fastenings, a normally pendant forked lever pivotally supported from the first mentioned plate to swing to position transverse to and embracing said lever and adapted when so swung to hold said second plate in position for protecting said fastenings, a slide adjustable along the forked portion of the bar to embrace one side of the lever, and a lock adapted to secure the slide to the bar while preventing the swinging of the lever in a direction away from the side embraced by the slide.

In testimony whereof I affix my signature in presence of two witnesses.

WILLIAM L. McCRAY.
